UNITED STATES PATENT OFFICE.

OZIA A. ESSIG, OF CANTON, OHIO, ASSIGNOR TO THE ESSIG PIVOT WINDOW COMPANY, OF STARK, OHIO, A CORPORATION OF OHIO.

TRANSOM-LOCK.

SPECIFICATION forming part of Letters Patent No. 739,300, dated September 22, 1903.

Application filed September 11, 1902. Serial No. 122,953. (No model.)

To all whom it may concern:

Be it known that I, OZIA A. ESSIG, a citizen of the United States, residing in Canton, in the county of Stark and State of Ohio, have 5 invented certain new and useful Improvements in Transom-Locks; and I do hereby declare that the following is a full, clear, and exact description of the same, reference being had to the annexed drawings, making a 10 part of this specification, and to the figures of reference marked thereon, in which—

Figure 1 is a view showing a portion of the transom and the same properly locked. Fig. 2 is a similar view, except that the transom is unlocked and in condition to be swung upon its 15 hinges. Fig. 3 is a transverse section showing a transom locked. Fig. 4 is a transverse section showing the transom unlocked and partially swung upon its hinges. Fig. 5 is a 20 detached view of the lock-plate.

The present invention has relation to transom-locks; and it consists in the different parts and combinations of parts hereinafter described, and particularly pointed out in the 25 claim.

Similar numerals of reference indicate corresponding parts in all the figures of the drawings.

In the accompanying drawings, 1 represents 30 the transom-rail to which the lock is to be attached.

The lock proper consists of the plate 2, fixed in any convenient and well-known manner to the transom-rail 1, to which plate is 35 pivotally connected the lock-lever 3, which may be done by a rivet or a screw, as desired, as the only object is to pivotally connect the lock-lever 3 to the plate 2 for the purpose hereinafter described. The lock-plate 4 is 40 secured to the transom-sill 5, or it may be attached at any other desired point—as, for instance, if the transom is to swing from one of its ends then of course the lock-plate 5 should be attached to the side casing. The 45 lock-plate consists of an angled piece of metal, as illustrated in Figs. 3 and 4, and is so located that when the transom proper is brought into a normal or closed position the

bottom or lower end of the lock-lever 3 will engage the vertical portion of the lock-plate 4, as illustrated in Figs. 1 and 3. It will be understood that when the transom is closed or turned in the act of closing the transom the lock-lever 3 should be turned into the position illustrated in Fig. 2, so that the bottom or lower end of the lock-lever 3 will clear the vertical portion of the lock-plate 5, after which the lock-lever is turned upon its pivotal point and brought into the position shown in Fig. 1. For the purpose of allowing the bottom or lower end of the lock-lever 3 to clear the lock-plate 4 without turning the lock-lever to any great distance beyond a vertical position the bottom or lower end of said lever is curved at an angle to its pivotal point. For the purpose of holding the lock-lever after it has been turned so as to clear the vertical portion of the lock-lever 4 the stop-pin 5^a is provided and is formed integral with the plate 2 if desired. For the 70 purpose of preventing the lock-lever 3 from accidentally turning upon its pivotal point when the transom is locked the stop-pin 6 is provided, which stop-pin is located at a point where it will properly hold the lock-lever so 75 as to securely lock the transom. It will be understood that by my peculiar arrangement I am enabled to hold the lock-lever in proper position to clear the lock-plate.

The stop-pins 5^a and 6 are so located upon 80 plate 2 that the lock-lever 3 will rest upon said stop-pins regardless of the position of the lever, either to lock or unlock the transom. The stop-pin 5^a should be so located that it will stop the lock-lever 3 before the 85 top or upper edge of the curved portion of the lock-lever 3 strikes the bottom or under side of the stop-pin 6, this being desirable to prevent the breaking of the stop-pin 6 by sudden throw of the lock-lever.

Having fully described my invention, what I claim as new, and desire to secure by Letters Patent, is—

The combination of a swinging or pivoted transom, and a plate secured to one of the 95 rails of the transom, a lock-lever provided

with a laterally-curved portion at its bottom or lower end, a lock-plate held in a fixed position and adapted to engage the lock-lever, and means for limiting the pivotal movement of the lock-lever, substantially as and for the purpose specified.

5 In testimony that I claim the above I have

hereunto subscribed my name in the presence of two witnesses.

OZIA A. ESSIG.
